US0D1077034S

(12) **United States Design Patent** (10) **Patent No.:** **US D1,077,034 S**
(45) **Date of Patent:** **** May 27, 2025**

(54) **CAMERA MOUNT**

(71) Applicant: **GoPro, Inc.**, San Mateo, CA (US)

(72) Inventors: **John George Muhlenkamp, IV**,
Brisbane, CA (US); **Scott Alberstein**,
San Francisco, CA (US); **Bessy Liang**,
San Jose, CA (US); **Huy Phuong**,
Nguyen, Alpine, UT (US); **Daniel J.**
Coster, Oakura (NZ); **Nicholas D.**
Woodman, Big Sky, MT (US); **Jesse**
Patterson, Pacifica, CA (US)

(73) Assignee: **GoPro, Inc.**, San Mateo, CA (US)

(**) Term: **15 Years**

(21) Appl. No.: **29/870,603**

(22) Filed: **Jan. 31, 2023**

Related U.S. Application Data

(62) Division of application No. 29/740,015, filed on Jun.
30, 2020, now Pat. No. Des. 982,065.

(51) **LOC (15) Cl.** **16-05**

(57) **CLAIM**

The ornamental design for a camera mount, as shown and
described.

DESCRIPTION

FIG. 1 is a front, upper, left perspective view of a camera
mount showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in the figures depict portions of the
camera mount that form no part of the claimed design.

1 Claim, 6 Drawing Sheets
